UNITED STATES PATENT OFFICE.

JAMES E. MURPHY, OF PORT JERVIS, NEW YORK.

CAR-COUPING.

SPECIFICATION forming part of Letters Patent No. 259,417, dated June 13, 1882.

Application filed February 6, 1882. (Model.)

To all whom it may concern:

Be it known that I, JAMES E. MURPHY, of Port Jervis, Orange county, in the State of New York, have invented a new and useful 5 Car-Coupler, of which the following is a specification, reference being had to the accompanying drawings.

The nature and object of my invention consist of the construction and arrangement of a 10 car-coupler, as will be hereinafter more fully described.

In the annexed drawings, Figure 1 is a detail under section of my improved car-coupler, taken through the lines *a a* in Fig. 3. Fig. 2 15 is the reverse or under surface of the detail section in Fig. 1. Fig. 3 represents one of the external lateral sides of my improved car-coupler, with the detail under section in Fig. 1 secured by bolts to a flat plate or cover having the same exterior lines as shown in Fig. 2, with braces, and represent the ordinary draw-head usually attached to railroad-cars.

Within the draw-head *A*, Fig. 1, I place the metallic bars *B B*, with hooks *C C*, the rear 25 ends of the bars overlapped and halved to each other and pivoted to or bolted through the draw-head *A* at the pin-hole *X*, as shown in Fig. 1. I also place within said bars *B B* a solid **C**-shaped metallic block, *D*, with arms *d d*, 30 made to fit snugly around the arrow-headed ends of the coupling-bar, and are designed, in connection with the grooves *c c*, the hooks *C C*, the bolts *e e*, and the springs *E E*, to hold the coupling-bar *G*, as shown in Fig. 1.

Placed in the space between the springs *E E* and the overlapped ends of the bars *B B* is 35 a cam, *F*, which may be bolted to the draw-head *A* between the bars *B B*, Fig. 1, and may be operated from either side of the car by 40 means of the crank *H*, Figs. 2 and 3, with any suitable leverage, so as to uncouple the cars by spreading the bars *C C*.

The coupling-bar *G*, Figs. 1, 2, and 3, is a straight metallic bar of proper length, broader 45 than thick, with beveled or rounded sides, and arrow-headed, and having two shoulders, *i i*, Figs. 1 and 2, the broad sides of the head being gradually depressed from the shoulders to the coupling-bar end *j*, and the lateral sides of 50 the head gradually tapering from the shoulders to the end *j*.

E E, Fig. 1, are two strong spiral springs, placed at right angles to the bars *B B*. A bolt passes horizontally through a clamp on either side of the draw-head *A*, and also passing horizontally through the bars *B B* and the springs *E E*, and similarly clamped on the opposite side of the draw-head, and properly secured or fastened at both ends. The pressure of the springs *E E* keeps the bars *B B* closed, 55 and will automatically relax to receive the coupling-bar when the essential force is applied, and may be relaxed at will by means of the cam *F*, operated as described. The springs *E E* automatically accommodate the bars *B B* 60 to the lateral movement of the cars coupled by my invention while rounding curves in the railroad-track. The inner sides of the bars *B B* at the grooves *o o* and the arms *d d* of the **C**-shaped block *D*, with the rounded bolts *e e* 65 passing vertically through the draw-head *A*, form a commodious receptacle for the coupling-bar *G*, and also form a smooth wall on both sides of the mouth or entrance, which allows the cars to be freely uncoupled by means of the cam *F* when operated as described. As the coupling-bar enters the draw-head, the head, 70 by pressing against the sides of the hooks *C C*, forces them apart, and as soon as the head has passed the same it enters the space between the arms *d d*, the springs *E E* throw the bars inward again, which couples the cars, and the block *D* stops the further passage of the coupling-bar. The mouth or entrance of the draw-head as far as the grooves *o o* is 75 concave, *t t*, as shown in Fig. 3.

When the draw-head of one car in which one head of the coupling-bar is fixed is higher than that of another car, as in the case of a loaded car and an empty car which it is desired to couple, such difference of elevation is obviated by slightly spreading the bars *B B*, in which the bar-head is fixed, by means of the cam *F*. The grooves *o o* in the hooks *C C* keeping the coupling-bar parallel with the bars *B B*, the other head of the coupling-bar will take a downward direction and strike the lower side of the concave mouth of the draw-head, and will then couple the cars, substantially as described. 80 85 90 95 100

A raised brace, *K*, Fig. 3, cast solid with the upper plate of the draw-head *A*, is intended to

resist the shock of the cars violently meeting and keep the draw-head from being forced out of its proper place.

5 Pin-holes u are placed in each end of the coupling-bar, for use in coupling a car supplied with my invention with a car made with the ordinary draw-head.

The ordinary link and pins may be used to couple cars supplied with my invention in case 10 of the want of my coupling-bar; but links are not a complete substitute for my coupling-bar.

My coupler is composed of two parts, the second part formed, like the first, with a coupling-bar, as described.

15 The grooves o run horizontally the whole

length of the hooks C and correspond to the rounded or beveled sides of my coupling-bar.

The draw-head A is to be secured to the under side of the floor or platform of the car in place of the ordinary draw-head.

20

I claim—

The arrangement of the draw-head A, the coupling-bars B, the hooks C C, the bolts e , the grooves o , the springs E E, the cam F, the crank H, with the block D and arms d , 25 and the brace K, substantially as described.

JAMES E. MURPHY.
